MULTIPLE UTILITY GRINDER

Joseph J. Miller, San Francisco, Calif.

Application April 17, 1953, Serial No. 349,530

10 Claims. (Cl. 51—166)

The present invention relates to improvements in a multiple utility grinder, and its principal object is to provide a grinder of the character described in which an annular series of grinding wheels are mounted in a turret in such a manner that any one of them may be moved into its proper position with respect to a grinding station.

It is a further object of my invention to provide a common operating means for all of the grinding wheels with control means operative to apply power only to the grinding wheel disposed at the grinding station, while all of the other grinding wheels remain inactive.

It is still further proposed to provide an individual guard for each grinding wheel, each guard having a discharge conduit for flying particles of dust adapted to line up with a common discharge when the guard is disposed at the grinding station.

Another object of the present invention is to provide for a variable speed transmission between a motor and the grinding wheels to compensate for loss of surface speed due to the wearing down of the grinding wheels.

A still further object of the invention is to provide for a mounting means for the turret on one side of a supporting pedestal which may be readily duplicated on the other side of the pedestal for doubling the capacity of the machine.

And finally it is proposed to provide a machine of the character described that is relatively simple in construction, easy to adjust and operate, economic in operation, and in which all the parts and particularly the wheel at the operating station are readily accessible, resulting in saving in time and labor.

Further objects and advantages of my invention will appear as the specification progresses, and the new and useful features of my Multiple Utility Grinder will be fully defined in the claims attached hereto.

The preferred form of my invention is illustrated in the accompanying drawings, forming part of this application, in which:

Figure 1 shows an end view of my Multiple Grinder; Figure 2, a side view of the same, with parts shown in section;

Figure 3, an enlarged detail section taken along line 3—3 of Figure 2; and

Figure 4, a section taken along line 4—4 of Figure 3.

While I have shown only the preferred form of the invention, it should be understood that various changes or modifications may be made within the scope of the claims attached hereto without departing from the spirit of the invention.

Referring to the drawings in detail, my Multiple Grinder comprises in its principal features a pedestal 1 terminating, at its upper end, in a transverse housing 2, a horizontal shaft 3 revolvable in the housing and having a large gear wheel 4 fixed to the outer end thereof, a cam 5 fixed to the outer end of the housing near the gear wheel, a drum or turret 6 revolvable or turnable on the housing and provided with an annular series of stub shafts 7 having grinding wheels 8 secured thereon outside the

2

drum, a roller 9 on each stub shaft cooperating with the cam in establishing driving relation between the gear wheel and the stub shaft disposed at the grinding station, a motor 11 vertically adjustable in the pedestal and a driving connection including a belt 12 between the motor and the main shaft 3 designed to change the speed ratio in response to vertical adjustments of the motor.

The pedestal 1 may be of any suitable form and height and is hollow to accommodate various drive elements therein. The housing 2 lies transversely over the pedestal and has reduced cylindrical extensions 13 projecting in opposite directions, which makes it possible to support two complete turret arrangements thereon. Only one has been shown as being sufficient to explain the present invention.

The shaft 3 is revolvable in the housing in bearings 14 and has the gear wheel 4 secured upon the outer end thereof, the gear wheel being in the form of a disc having an inwardly off-set rim section to bring the gear teeth in conveniently close relation to the cam 5.

The latter has a generally circular cam face of slightly longer diameter than that of the gear wheel and is fixed upon the end of the housing extension 13, as at 15. At the operating or grinding station, which is located at the horizontal central plane of the turret, the surface of the cam is cut back, and at this location the cam has a fitting 16 secured thereto which provides a short cam face 17 (see Figure 4) concentric with, but drawn to a slightly smaller diameter than the main cam surface, with suitable graded approaches 18 merging into the main cam face.

The fitting 16 also carries an outer cam 19 spaced from the cam 17 and concentric therewith so as to form a track 20 with the same, the outer cam merging into the inner face of the drum 6 through approaches 21 graded to run parallel to the approaches 18.

The drum 6 is revolvable on the extension 13 of the housing 2, through a bearing 22, and comprises a hub 23, an end member 24 and a cylindrical wall 25 extending over the cam 5 and the gear wheel 4 and beyond the same and being made of an inner diameter in excess of the outer diameter of the cam, so as to form a track 26 therewith.

The drum has the annular series of stub shafts 7 mounted therein, with the rollers 9 on the shafts arranged to ride in the track 26 and the track 20 communicating therewith. The shafts are secured to the inner face of the drum by means of drag links 27 pivoted, at one end, as at 27', in small brackets 28 projecting inwardly from the drum in evenly spaced relation and terminating, at their free ends, in sleeves 29 extending transversely of the drum and having the stub shafts 7 revolvably mounted therein, through bearings 30.

The free ends of the stub shafts 7 and the sleeves 29 extend through an end plate 31 secured upon the free end of the drum and are guided in slots 32, which are made arcuate on the radii of the pivots 27', to allow of swinging movement of the drag links in the manner necessary for the operation of the machine.

It will be noted that, when the drum is revolved or turned, it drags the stub shafts 7 along with it, through the drag links 27, and that the swinging movement of the drag links is controlled by the rollers 9 riding in the tracks 26 and 20, respectively. As long as the rollers are disposed in the tracks 26, which extends over the major portion of the cam 5, the shafts are held relatively close to the wall of the drum. When the rollers enter the track 20, they are crowded inwardly, that is, toward the center of the drum, and move the shafts correspondingly, as shown in Figure 4.

The stub shafts carry pinions 33 arranged in opposing relation to the gear wheel 4, and as long as the rollers 9 ride in the main track 26, the pinions are held out of

engagement with the gear wheel, but when the rollers 9 pass through the short track 20, carried by the cam 5 at the grinding station, the pinions are made to enter into engagement with the gear wheel, attaining a position of full engagement at the central horizontal plane of the drum, as shown in Figure 4.

Each stub shaft 7 is automatically locked in central position at the grinding station by means of a spring-pressed plunger 34 cooperating with a pin 35 projecting from the end wall 24 of the drum opposite each shaft, the plunger having a head 36 with a central recess fitting the pin and a slanting approach 37 to the recess, whereby on a turning movement of the cylinder, the plunger is first pushed back by the pin bearing on the slanting approach and then snaps into place over the pin for locking the same in central position.

The engagement may be released manually by means of the handle 38 pivoted to the housing 2, as at 39 (see Figure 2) which operates the plunger through a link 40 for retracting the plunger.

The main shaft 3 carrying the gear wheel 4 is driven by the motor 11 through a chain drive comprising a chain 41, a sprocket 42 on the main shaft 3 and a sprocket 43 on an intermediate shaft 44 mounted transversely in the pedestal, and through a V-belt drive including a pulley 45 on the shaft 44, a pulley 46 on the motor shaft and a V-belt trained over the two pulleys.

Since a grinding wheel works most satisfactorily at a given surface speed, and since the surface speed naturally decreases as the diameter of the wheel decreases, due to wear, it is desirable to provide a simple means for varying the R. P. M. speed to compensate for a decrease in surface. This I accomplish by making the pulley 46 of the Vari-Speed type, well-known in the market, which is built on the principle of making one of the flanges of the V-pulley movable with respect to the other and of using spring pressure for urging the movable flange toward the fixed flange. Thus the active diameter of the pulley is determined by the belt pressure operating against spring pressure.

In the present structure, the variable pulley 46 is mounted on the motor shaft, and the motor is mounted in a cage 47 slidable in the pedestal and suspended from a screw 48 operable to raise and lower the cage when rotated by means of a bevel gear drive 49 and a handle 50.

In the position shown in Figure 2, the motor is set relatively low, causing the V-belt to engage in the bottom of the pulley groove and driving the gear wheel 4 and the grinding wheel at the grinding station at relatively low speed, which would give the proper surface speed for a new grinding wheel.

If it becomes desirable to increase the speed ratio, the operator merely raises the motor by operation of the handle 50. This causes the belt to climb out of the bottom of the groove in the pulley 46, due to the spring action, and to use a larger diameter of the pulley for insuring a higher speed ratio. Thus, by gradually raising the motor, the operator is able to compensate for the gradual wear on the grinding wheel and to maintain a uniform surface speed.

Each of the grinding wheels is provided with its own guard 51, the guards being mounted upon the outer ends of the sleeves 29 and moving with the grinding wheels to the grinding station.

Each guard is cylindrical in form to surround its grinding wheel in slightly spaced relation thereto, and has an opening, as at 52, to give access to the wheel at the grinding station where a suitable tool or work rest is provided, as at 53.

Each guard is also provided with a discharge conduit 54 for dust particles, leading centerwise to a collecting chamber 55 from which it is exhausted through a port 56 connecting with a hose 57.

The operation of my multiple utility grinder should be readily understood from the foregoing description.

Upon selecting the grinding wheel he intends to use, the operator turns the drum to bring the desired wheel opposite the grinding station. During this operation the rollers 9 ride in the tracks 26 and 20, respectively, holding all the pinions 33 except one out of engagement with the gear wheel 4, while one of them passes through the grinding station and passes through a position of engagement and out again.

10 The operator holds the handle 38 to prevent locking at the grinding station until the selected grinding wheel reaches the station, when he releases the handle to automatically lock the wheel in central position.

15 The operator may then inspect the condition of the selected gear wheel and adjust the motor by operation of the handle 50 to insure the proper surface speed.

20 Next, he will press one of the buttons 58 to start the motor, and driving power will be transmitted from the motor through the V-belt drive 12, the sprocket drive 41, the shaft 3 and the gear wheel 4 to the one grinding wheel disposed at the grinding station, while all the other grinding wheels remain inactive, due to their relative positions with regard to the cam 5.

I claim:

25 1. In a multiple grinder, a main shaft rotatable on a horizontal axis and having a gear wheel mounted thereon, a fixed member having a co-axial annular cam adjacent the rim of the gear wheel, a drum turnable on the axis of rotation and having an inner annular cam facing the first cam to form a track therewith, a plurality of drag links pivoted to the inner wall of the drum and having stub

30 shafts revolvable in the free ends thereof, rollers on the stub shafts extending into the track, and pinions on the stub shafts facing the gear wheel, the track being positioned with respect to the gear wheel for normally spacing the pinions therefrom, and the fixed cam having means for urging any one of the pinions into meshing engagement with the gear wheel when the said pinion passes a designated station due to the turning movement of the drum.

40 2. In a multiple grinder, a main shaft rotatable on a horizontal axis and having a gear wheel mounted thereon, a fixed member having a co-axial annular cam adjacent the rim of the gear wheel, a drum turnable on the axis of rotation and having an inner annular cam facing the

45 first cam to form a track therewith, a plurality of drag links pivoted to the inner wall of the drum and having stub shafts revolvable in the free ends thereof, rollers on the stub shafts extending into the track, and pinions on the stub shafts facing the gear wheel, the track being positioned with respect to the gear wheel for normally spacing the pinions therefrom, and the fixed cam having

50 means for urging any one of the pinions into meshing engagement with the gear wheel when the said pinion passes a designated station due to a turning movement of the drum, and the drum having means for automatically locking the same when the said pinion has reached a position of full engagement with the gear wheel.

55 3. In a multiple utility grinder, a shaft rotatable on a horizontal axis and having a gear wheel mounted thereon, a drum turnable on the axis of rotation to encircle the gear wheel, a plurality of stub shafts carried by the drum

60 outside the gear wheel so as to be movable with the drum and with respect thereto, the stub shafts having pinions facing the gear wheel, and cam means operable on the

65 stub shafts for normally keeping the pinions out of engagement with the gear wheel, the cam means including means for urging any one of the pinions into engagement with the gear wheel when the stub shaft carrying the pinion passes a designated station due to the turning movement of the drum.

70 4. In a multiple utility grinder, a shaft rotatable on a horizontal axis and having a gear wheel mounted thereon, a drum turnable on the axis of rotation to encircle the gear wheel, a plurality of stub shafts carried by the drum

75 outside the gear wheel so as to be movable with the drum

and with respect thereto, the stub shafts having pinions facing the gear wheel, and cam means operable on the stub shafts for normally keeping the pinions out of engagement with the gear wheel, the cam means including means for urging any one of the pinions into engagement with the gear wheel when the stub shaft carrying the pinion passes through a designated station due to the turning movement of the drum, and the drum having means co-operating therewith for locking the same when the pinion has reached a position of full engagement with the gear wheel.

5. In a multiple grinder, a drum mounted for turning movement on a horizontal axis, a gear wheel revolvable within the drum, a drag link pivoted to the inner face of the drum and having a shaft revolvable in the free end thereof, a pinion on said shaft opposite the gear wheel, and a cam mounted within the drum and active on the shaft for normally holding the pinion out of engagement with the gear wheel.

6. In a multiple grinder, a drum mounted for turning movement on a horizontal axis, a gear wheel revolvable within the drum, a drag link pivoted to the inner face of the drum and having a shaft revolvable in the free end thereof, a pinion on said shaft opposite the gear wheel, and a cam mounted within the drum and active on the shaft for normally holding the pinion out of engagement with the gear wheel, the cam having means for urging the pinion into engagement with the gear wheel when the shaft passes through a designated station on a turning movement of the drum.

7. In a machine of the character described, a cam having a major cylindrical portion drawn to the same diameter and a minor cylindrical portion of less diameter, with graded approaches between the two portions, the minor portion having a concentric cam face opposing the same to form a track therewith, with similarly graded approaches leading to the latter cam face, and a member turnable on the cam having means for dragging a roller over the cam and through the track, the roller having a shaft revolvable therein with a pinion on the shaft, and a gear wheel revolvable concentric with the cam and in the plane of the pinion, with the pinion clearing the gear wheel while the roller passes over the major portion of the cam and engaging therewith when the roller passes through the track.

8. In a multiple grinder, a member turnable about a central axis, an annular series of shafts revolvable in said member and having grinding wheels thereon, a rotary gear wheel mounted inside the series of shafts,

pinions on the shafts in coplanar relation with the gear wheel and normally spaced therefrom, and means responsive to a turning movement of the said member for meshing any one of the pinions with the gear wheel as the said pinion passes through a designated station, the latter means comprising a fixed cam mounted adjacent the gear wheel and rollers on the shafts riding on the cam, and the cam having a major section dimensioned to space the pinions with respect to the gear wheel and a minor track section crowding a roller passing therethrough inwardly to force its companion pinion into engagement with the gear wheel.

9. In a multiple grinder, a drum mounted for turning movement on a horizontal axis, a gear wheel revolvable within the drum and having a continuous set of gear teeth thereon, an annular series of spaced pinions carried by the drum coplanar with the gear wheel and normally disconnected therefrom, and means for establishing continuous driving gear connection between any one of the pinions and the gear wheel when said pinion passes through a designated station on a turning movement of the drum.

10. In a multiple grinder, a drum mounted for turning movement on a horizontal axis, a gear wheel revolvable within the drum and having a continuous set of gear teeth thereon, an annular series of spaced pinions carried by the drum coplanar with the gear wheel and normally disconnected therefrom and means for establishing continuous driving gear connection between any one of the pinions and the gear wheel when said pinion passes through a designated station on a turning movement of the drum, the pinions having grinding wheels mounted co-axially therewith.
